[57] CLAIM

The ornamental design for a three pillow massage cushion, as shown and described.

DESCRIPTION

FIG. 1 is a top plan view of a three pillow massage cushion showing my new design;

FIG. 2 is a side pictoral view thereof;

FIG. 3 is a bottom plan view thereof;

FIG. 4 is a right side elevational view thereof, the undisclosed left side elevational view being a mirror image;

FIG. 5 is a rear elevational view thereof; and,

FIG. 6 is a front elevational view thereof.

The inside surfaces between the cushions not shown are plain and unornamented.
